[57] **CLAIM**

The ornamental design for a hanger assembly, as shown and described.

DESCRIPTION

FIG. 1 is an isometric view of a hanger assembly broken away for the purpose of illustrating indeterminate length, according to my new design;

FIG. 2 shows an end elevation of a hanger assembly, the opposite end view being identical;

FIG. 3 shows a front elevation of a hanger assembly, the rear view being identical;

FIG. 4 shows a top view of a hanger assembly broken away for the purpose of illustrating indeterminate length; and,

FIG. 5 shows a bottom view of a hanger assembly broken away for the purpose of illustrating indeterminate length.
